ABSTRACT OF THE DISCLOSURE

This disclosure teaches the use of gas-turbine exhaust as a combustion-supporting gas in hydrocarbon reformers. Gas-turbine exhausts containing from 16 to 19 percent by volume of O₂ and at from 700° F. to 1000° F. are preferred. An apparatus especially suited to this task is also disclosed. Multiple levels of burners accommodate duct work under burner platforms.

This disclosure relates to hydrogen production by high-temperature reforming of hydrocarbons. More particularly the invention resides in such a hydrogen plant associated with gas turbines, as for example an ammonia synthesis plant wherein gas turbines are used to drive pumps, refrigeration compressors and the like. A process and a system are taught whereby fuel economy is stepped up.

Mechanical properties of metals limit the temperatures at which gas turbines may be operated to from 700° F. to 1000° F. Generally, large volumes of excess air are necessary in order to keep turbine-blade temperatures down. Accordingly turbine exhaust contains from 16 to 19 percent of oxygen at from 700° F. to 1000° F. Basically this teaching takes advantage of high temperature, oxygen-rich turbine exhaust to promote combustion in reformer furnaces. By this expedient furnace chambers in ammonia synthesis plants (for example) can be reduced in size by from ten to thirty percent. Further, the fuel required to maintain furnace chambers at reforming temperatures is vastly reduced. Utilizing the exhaust of gas turbines improves their competitive position vis-a-vis steam-turbine or electric-motor drives. This approach is especially facile in wall-fired reformer furnace designs with elongated burners where ductwork for the gas turbine exhaust can be conveniently positioned to support platforms for access to the burners.

These and other advantages will appear more fully from the accompanying drawings wherein:

FIGURE I is a sketch illustrating the relationship of gas turbine and reformer furnace according to this invention.

FIGURE II is an elevation view in section of a reformer furnace arranged for using gas turbine exhaust to support combustion.

FIGURE III is an elevation view in section and taken along line 3—3 of FIGURE II.

FIGURE IV is an enlarged section through a linear burner adapted to receive gas turbine exhaust.

FIGURE V is a section taken along line 5—5 of FIGURE IV.

As best seen in FIGURE I, exhaust from gas turbine 1 is delivered via ducts 2 to burners 3 where it supports combustion of a suitable fuel (generally gaseous) introduced via fuel lines 4. To produce a mixture of H₂ and CO, a hydrocarbon (such as methane or propane) along

2

with a suitable oxidant such as H₂O and/or CO₂, is coursed from inlet manifolds 6 through furnace tubes 7 which are filled with a suitable catalyst such as granular nickel oxide to outlet manifolds 8 all in a manner well known to those familiar with this art.

Temperatures in excess of 2000° F. are desirable in furnace chamber 9 for hydrocarbon reforming. Toward this objective elongated settings 11 include side walls 12 which are relatively close to tubes 7. Burners 3 are arranged in elongated tile troughs 13 along side walls 12 so that heat from these burners washes side walls 12 to heat them to uniform incandescence so that substantially the entire surfaces of these side walls act as heating elements.

It is important that impingement of flames on catalyst filled tubes 7 be avoided. So combustion of the gaseous fuel is contained from burner tips 14 to the exits 16 of troughs 13 so that tubes 7 do not see flame.

Delivery ducts 2 are internally lined with insulation. Dampers 17 and reach rods 18 offer control of turbine exhaust flow.

Combustion products are vented, with the aid of induced draft fans 19 by way of convection section 21 and stacks 22.

It will be understood by those skilled in furnace design that wide deviations may be made from the shown embodiment without departing from the spirit of invention as set forth in the claims.

What is claimed is:

1. A process for manufacturing H₂ and CO and comprising the steps of defining a furnace chamber, providing at least one burner operatively associated with the furnace chamber for maintaining the temperature therein in excess of 2000°, delivering a suitable fluid fuel to the burner, providing a supply of gas-turbine exhaust at a temperature in the range of from 700° F. to 1000° F. and with an O₂ content in the range of from 16% to 19% by volume, delivering the gas-turbine exhaust to the burner in a sufficient supply to support substantially complete combustion of the fuel, coursing a hydrocarbon stream and a suitable oxidant through at least one granular-catalyst-filled tube in the furnace chamber for reforming the hydrocarbon to produce H₂ and CO.

2. The combination of a gas turbine having a gas-turbine exhaust outlet and a furnace for producing a mixture of H₂ and CO wherein the furnace includes

an elongated setting having side walls and enclosing a furnace chamber, at least one linear burner arranged along each of the side walls for heating that side wall to incandescence, means for introducing a suitable fluid fuel to each of the burners,

at least one granular-catalyst-filled tube mounted in the chamber approximately midway between the side walls, means for coursing a hydrocarbon stream along with a suitable oxidant through the tube for reforming the hydrocarbon to produce H₂ and CO, means for venting combustion products from the combustion chamber,

delivery means connecting the gas-turbine exhaust outlet with each of the burners whereby the gas-turbine

exhaust serves as combustion-supporting gas for the fuel.

3. The combination of claim 2 with the burners mounted at more than one level on each of the side walls.

4. The combination of claim 3

with the delivery means including a plurality of ducts arranged along both of the side walls and below the burner levels,
a platform arranged for burner access and supported on at least one of the ducts.
